UNITED STATES PATENT OFFICE.

WALTER S. MCKEE, OF CHICAGO, ILLINOIS, AND FRANK E. JOHNSON, OF SALT LAKE CITY, UTAH, ASSIGNEES TO AMERICAN MANGANESE STEEL COMPANY, OF AUGUSTA, MAINE, A CORPORATION OF MAINE.

CRUSHER JAW-PLATE.

1,187,160.

Specification of Letters Patent. Patented June 13, 1916.

Original application filed January 25, 1915, Serial No. 4,088. Divided and this application filed February 26, 1916. Serial No. 80,561.

To all whom it may concern:

Be it known that we, WALTER S. MCKEE, a citizen of the United States, and a resident of Chicago, in the county of Cook and 5 State of Illinois, and FRANK E. JOHNSON, a citizen of the United States, and a resident of Salt Lake City, in the county of Salt Lake and State of Utah, have made and invented certain new and useful 10 Improvements in Crusher Jaw-Plates, of which the following is a specification.

This invention relates to crusher jaw plates; an object of the present invention being to provide a jaw plate which is made 15 up of a plurality of replaceable sections, each section being so designed and constructed that the several sections may be rigidly locked together and the corrugations and ribs thereof held in alinement before the 20 crusher jaw plate is assembled in the crushing machine.

This application is a division of our co-pending application #4088, filed Jan. 25, 1915.

25 A further object is to provide improved means for locking together the several sections of a crusher jaw plate, the securement between the several sections being such that the jaw plate may be handled and transported as a single unit.

30 A further object is to accomplish the above-mentioned ends in a practical and efficient manner, and with these and other objects in view, our invention resides in the combination and arrangement of parts and 35 in the details of construction hereinafter described and claimed, it being understood that changes in the precise embodiment of the invention can be made within the scope 0 of what is claimed without departing from the spirit thereof.

The preferred embodiment of our invention is disclosed in the accompanying drawing, wherein:—

45 Figure 1 is a view in front elevation of our novel sectional jaw plate, portions thereof being broken away to more fully disclose the structural details thereof; Fig. 2 is a view in vertical section taken on the line 2—2 of Fig. 1; Fig. 3 is a view in section taken on the line 3—3 of Fig. 1; Fig. 4 is a fragmental view in plan, illustrating the back of the crusher jaw plate; Fig. 5

is a view in vertical longitudinal section of a slightly modified form of crusher jaw 55 plate.

Referring specifically to the several views, the crusher jaw plate is made up of a plurality of sections 10, 11, 12 and 13, these sections being identical and interchangeable, 60 with the exception of the top section 13, which is of the nature of a wedge or key, and has the upper and lower surfaces thereof oppositely beveled.

In crushing ore and other material, the 65 lower extremity of the crusher jaw plate is exposed to the greatest wear, and for this reason our improved jaw plate is made up of sections, allowing the lowermost section to be replaced from time to time after it 70 has become worn beyond use, each section thereabove being moved down one space, thus preserving the continuity of the wearing face of the crusher jaw plate. In order to facilitate the replacement of the lowermost section of the jaw plate, and to insure 75 the proper alinement of the various sections, we provide each section with an undercut or dove-tailed slot 14, into which is forcibly driven a beveled holding key 15. 80 The various sections which go to make up a jaw plate are accordingly held in rigid relation and proper alinement by the holding key, allowing the jaw plate to be inserted into or removed from a crushing machine and handled as though it were an integral casting.

The holding key 15 is provided with an opening 16 with which communicates a recess 17. Each section of the jaw plate, with 90 the exception of the top wedge-section, is provided with a recess 18, the location of which is such that it exactly alines and registers with the recess 17 in the holding key when the section is occupying the lowermost 95 position in the crusher jaw plate, and the holding key is in its final and seated position. This provision of openings and recesses allows a slug or locking member 19 to be inserted through the opening 16 within 100 the key and deposited within the recess 18 of the lowermost jaw plate section, this being accomplished while the holding key is slightly offset from its final position. The holding key is then forcibly driven into its 105 final position, bringing the slug or locking

member against the sides of the recess 17 and preventing the further movement of the holding key.

A somewhat similar arrangement is disclosed in Fig. 5, wherein it will be observed that the holding key is provided with but a single aperture 20, which is adapted to aline with one of the recesses 21, with which each of the sections of the jaw plate is provided.

10 The slug or locking member 22 in this instance is of such size that having once been forced into the alined openings of the key and jaw plate section, it is held against accidental displacement therefrom.

15 The various sections of our improved jaw plates are not only rigidly secured together, but the holding means is locked against displacement, thus allowing the jaw plates to be handled and transported as though

20 formed as a single casting. The replacement of the lowermost section after it has become excessively worn is conveniently accomplished by removing the entire jaw plate from the crushing machine, after which, the locking member and holding key may be easily removed and the various changes in the sections of the jaw plate conveniently made.

What we claim is:—

30 1. A crusher jaw plate comprising a plurality of sections, a key engaging said sections and holding the same in alinement, and means engaging said sections and said holding key preventing the accidental detachment thereof.

35 2. A crusher jaw plate comprising a plurality of sections, a key engaging said sections and holding the same in alinement, and a locking member engaging said key and 40 said sections, holding the former against accidental detachment.

Copies of this patent may be obtained for five cents each, by addressing the "Commissioner of Patents, Washington, D. C."

3. A crusher jaw plate comprising a plurality of interchangeable transverse sections 45 provided with alined recesses, a key positioned within said recess and locking means engaging one of said sections and said key, and holding the same in their assembled relation.

4. A crusher jaw plate comprising a plurality of interchangeable transverse sections 50 provided with alined openings, a key fitting within said openings and holding said sections in rigid alinement, said key provided with an opening therein, said sections provided with recesses, one of which is adapted 55 to aline with the opening within said key, and a locking member fitting within the opening within said key and a recess within one of said sections.

5. A crusher jaw plate comprising a plurality of interchangeable sections, each provided with an undercut recess, a beveled key fitting within said recesses and rigidly holding said sections in alinement, and locking means engaging one of said sections and said key and holding the same in their assembled relation.

Signed at Chicago, in the county of Cook and State of Illinois, this 23 day of February, 1916.
